UNITED STATES PATENT OFFICE.

EDWARD F. WARD, OF ATLANTA, GEORGIA.

EGG-CASE.

SPECIFICATION forming part of Letters Patent No. 747,518, dated December 22, 1903.

Application filed February 14, 1903. Serial No. 143,458. (No model.)

To all whom it may concern:

Be it known that I, EDWARD F. WARD, a citizen of the United States, and a resident of the city of Atlanta, county of Fulton, and State of Georgia, have invented a new and useful Improvement in Egg-Cases, of which the following is a specification.

The object of my invention is to provide a case of this class which will be cheaper, more durable, and efficient than those heretofore made and which may be folded into a small space when not in use. These and other objects I accomplish by means of my invention, one embodiment of which is hereinafter disclosed.

For a more particular description of my invention reference is to be had to the accompanying drawings, forming a part hereof, in which—

20 Figure 1 is a plan view of a case embodying my invention, the case being shown open. Fig. 2 is a plan view of a closed case. Fig. 3 is a sectional view taken on the line 3 3 of Fig. 2. Figs. 4 and 5 are diagrammatic plan views showing the case in a partially-folded and folded condition. Fig. 6 is a side elevation of a folded case. Fig. 7 shows the blank from which the case is folded, and Figs. 8 and 9 show the blanks of the fillers or partitions.

30 Throughout the various views similar reference characters designate similar parts.

The blank from which my improved case is formed may be of cardboard, or thick paper, or any other suitable material, and comprises 35 the rectangular sides 1, 2, 3, and 4, which are bounded by the edges or folding-lines 5, 6, 7, 8, 9, 10, and 11, and the edges 7 and 11 are united by means of a flap 12, which extends from the edge 11. Folding-lines 13 and 14 run parallel to the lines 5 and 6, and from them extend flaps 15, 16, 17, 18, 19, 20, 21, and 22, which form the top and bottom of the case. The flaps attached to each line are provided with registering slits 23 and 24, respectively. 40 45 When the case is erected and closed, the flaps 17 to 22, inclusive, cover the entire top and bottom, but not adjacent to the edges of the side, because the strips between the lines 5 and 13 and 6 and 14, respectively, are folded inwardly on the lines 5 and 6, as indicated in Fig. 3, so that these strips rest against the

sides 1, 2, 3, and 4, and these flaps extend at right angles to the strips.

The filler or partitions may be made for any number of eggs that the case is designed to 55 carry. In the embodiment of my invention herein described the case is made to carry a dozen eggs, and the partitions are made accordingly. These partitions comprise two separate sections 25 and 26. The section 25 is 60 provided with corner-pieces 27, 28, 29, 30, 31, 32, 33, and 34, which are made a little longer than the distance between the folding-lines 5 and 6 and are bounded by the edges or folding-lines 35, 36, 37, 38, 39, 40, 41, 42, 43, 44, 45, 65 46, and 47. Between these corner-pieces are parts 48, 49, 50, and 51, whose width is equal to the distance between the lines 5 and 6 less the width of the strips, so that they are adapted to fit between the top and bottom of the 70 case. Slits 52, which extend from the upper edges of the parts 48 and 50, are adapted to engage slits 53, which extend from the lower edges of the parts 49 and 51.

The partition 26 is provided with the end 75 flaps 56 and 57, which are about the same width as the corner-piece 27, and in the transverse center of this partition are tabs or ears 58 and 59, which are adapted to pass through the slits 23 and 24, respectively, to hold the 80 top and bottom flaps in place. Extending upwardly from the lower edge of the partition are slits 60, which are adapted to engage the slits 52.

The case is erected from the blank by folding the strips between the lines 13 and 5 and 6 and 14, respectively, under the sides 1, 2, 3, and 4, and then folding the flaps 15 to 22, inclusive, back on the lines 13 and 14 until the said flaps are parallel to the sides and extend 85 as shown in Fig. 6. The sides are then folded at right angles on the lines 8, 9, and 10, and the flap 12 is secured to the side 1. The bottom flaps are then folded in place, and the case is then ready to receive the filling or partitions. 90 The filling or partitions are then folded, as indicated in Figs. 1 and 4, so that the corner-pieces 27 and 34, 28 and 29, 30 and 31, and 32 and 33 form two faces of a square prism which has vertical angles with a rectangular 100 prism formed by the engagement of the slits 52 with the slits 53 of the parts 48 and 50.

and 49 and 51, respectively. The central slits 52 are then engaged by slits 60 in the partition 26. The filling is then placed in the case, and the edges or flaps on the corner-pieces 27 to 34, inclusive, are placed between the sides 1, 2, 3, and 4 and the strips between the lines 5 and 13 and 6 and 14, respectively, and the ends of the flaps 56 and 57 are similarly inserted and preferably fixed to the sides 2 and 4. The tongue 59 is then made to pass through the slits 23 and locks the flaps 15, 17, 19, and 21 in place and when the case is filled the flaps 16, 18, 20, and 22 are similarly held by the tongue 59, which passes through the slits 24.

It is not necessary to fill the case immediately after erection. The flaps 15, 17, 19, and 21 may be opened and the case folded or collapsed, as indicated in Figs. 5 and 6, and the case may then be either stored or packed and transported.

The filling reinforces and strengthens the case by the corner-pieces 27 to 34, inclusive, which rest against the sides and extend beneath the strips from top to bottom, and also by the partitions which rest between the top and bottom flaps. The case is further strengthened by the said strips, which are folded back upon and reinforce the edges of the sides and materially stiffen the structure, particularly when the flaps are closed, as they engage these strips. For these reasons I have found that thinner paper or cardboard may be used on this structure than in any other of the same capacity heretofore made, and thinner paper may be used in the partitions, because the corner-pieces 27, 28, 29, 30, 31, 32, 33, and 34 hold the parts 48, 49, 50, and 51 in tension, so that they are stretched taut.

While I have shown my invention as embodied in an egg-case, it is obvious that by a slight change of proportions it may be adapted to receive fruit or vegetables or other articles and that when the case is filled with such articles it may be closed and sealed and used as a sealed package. This is of especial value in retailing eggs, which may be packed on the farm and the package sealed and dated before shipping, so that the consumer is protected and may know the genuineness of what he buys. This structure has the additional advantage of having the sides extend beyond the top and bottom flaps, so that the contents do not come in immediate contact with a rigid surface either above or below.

While I have shown and described one embodiment of my invention, it is obvious that many other embodiments may be made which are full equivalents, and so I regard all structures as equivalents which come within the scope of the following claims.

Having thus described my invention, what I claim is—

1. A blank for egg-cases and the like, comprising sides, a single and continuous strip

extending along each of the sides and adapted to fold thereon, independent flaps extending from said strip and adapted to form the top and bottom of the case.

2. A blank for egg-cases and the like, comprising sides, a continuous strip extending along the sides, and adapted to fold thereon, and flaps extending from the strip.

3. A blank for egg-case fillers and the like, comprising slotted sections and corner-pieces, the ends of which extend transversely beyond said slotted sections, said parts being so arranged that when the blank is bent up to interlock to form the cells, the said corner-pieces will be bent at approximately a right angle to each other, and their protruding ends will extend above and below the edges of the slotted sections.

4. A blank for egg-cases and the like, comprising sides, a single and continuous strip extending along each of said sides, and independent rectangular flaps extending from said strip.

5. A blank for egg-cases and the like, comprising sides, a continuous strip extending along said sides and adapted to fold thereon, and rectangular flaps extending from said strip which are adapted to form the bottom of the case.

6. A case for eggs and the like, comprising sides, strips folded against the said sides, flaps forming a bottom and a top extending from said strips, and fillers in said case with portions extending between said sides and strips.

7. A case for eggs and the like, comprising sides, a top and a bottom, a filler, and tongues passing through said top and bottom which connect them with said filler.

8. A case for eggs and the like, comprising sides, strips folded against the said sides, slotted flaps forming a top and bottom extending from said strips, fillers in said case and tongues on said fillers which are adapted to protrude through the slits and hold said filler to said top and bottom.

9. A case for eggs and the like, comprising sides, strips folded against said sides, flaps forming a bottom and top extending from said strips, fillers in said case with portions extending between said sides and strips, and means on said fillers for securing them to said flaps.

10. A case for eggs and the like, comprising sides, strips folded against the said sides, flaps forming a bottom and top extending from said strips, slotted fillers in said cases with portions extending between said sides and strips, and tongues on said fillers which are adapted to secure them to said flaps.

In testimony whereof I have signed my name to this specification in the presence of two subscribing witnesses.

E. F. WARD.
